GEAR HUB

Myron J. Zimmer, Chicago, Ill., assignor to Edward Katzinger Company, Chicago, Ill., a corporation of Illinois

Application June 13, 1934, Serial No. 730,446

12 Claims. (Cl. 74—432)

This invention relates to new and useful improvements in gear hubs and has for its object a construction wherein the hub is an integral and unitary part of the gear body and may be inexpensively created and formed.

With the above and other objects in view, as will be apparent, this invention consists in the construction, combination and arrangement of parts, all as hereinafter more fully described, 10 claimed and illustrated in the accompanying drawing, wherein:

Fig. 1 is a side elevation of a gear embodying the present invention illustrating the same as the driving gear of an egg beater; and

15 Fig. 2 is an edge elevation thereof.

While the present gear and its hub is of general application and use, it is designed particularly for use as the driving gear of an egg beater wherein the gear is mounted between the sides 20 of the beater frame and acts to space the sides of the frame.

Heretofore, it has been customary in order to mount the driving gear between the sides of the frame of an egg beater to provide a hub consisting of one or more individual pieces secured to the gear at its center and projecting outwardly from the body of the gear to bear against the inner surfaces of the egg beater frame. This type construction prevents any lateral play or 25 displacement on the part of the gear and at the same time spaces and braces the sides of the egg beater frame. The gears of the prior art including hubs made up of a number of separate parts has been difficult and expensive to 30 construct and assemble.

The present gear is designed to accomplish the purposes of the prior art gear and at the same time have all of its elements of the hub thereof formed integrally with the body of the gear, 35 thereby reducing the number of parts as well as the steps of construction and assembly.

Reference being had more particularly to the drawing, 10 designates the frame of an egg beater provided with a handle 11. The sides 12 40 of the frame 10 are spaced one from the other and rest parallel and at their lower ends are provided with mountings or bearings 13 in which the beaters 14 are mounted for rotation. Adjoining the lower ends of the sides 12 of the frame 10 and secured to the beaters 14 are gears 15 by which the beaters 14 are driven and rotated. A driving gear 16 is mounted between the sides 12 of the frame 10 and meshes with the gears 15 whereby the rotation of the driving 45

gear 16 causes the rotation of the gears 15 and consequently the beaters 14.

In order to create a hub at the center of the gear 16 in such form as to prevent any lateral play or displacement of the gear 16 and to fill 5 the space between the sides 12 of the frame, the body of the gear 16 at each side of the center thereof is cut to create a tongue 17, the inner end of which is integral with the body of the gear at a point adjoining the center thereof. 10 The formation of these tongues 17 from the body of the gear 16 creates a pair of diametrically disposed openings 18 in the body of the gear resting along a diameter of the gear and extending from the center of the gear toward the 15 periphery thereof. These tongues 17 are bent laterally to rest at right angles to the body of the gear 16 and extend outwardly to points adjoining the inner surfaces of the sides 12 of the frame 10. Here each tongue 17 is again bent at 20 right angles to create a bearing member 19 parallel to the gear 16 and extending across the line of the center of said gear to terminate approximately in the plane of the right angularly bent portion of the opposed tongue 17. The body of 25 the gear 16 at its center and the bearing members 19 of the tongues 17 which cross the line of the center of the gear 16 are each provided with a rectangular aligned opening 20 for the reception of the driving shaft 21.

The driving shaft 21 is rectangular in cross section and passes through circular openings in the sides 12 of the frame 10 and is received in 30 and passes through the rectangular openings 20 in the gear 16 and bearing members 19 so that 35 the shaft 21 is free to rotate in the sides 12 of the frame 10 and is rigidly and fixedly connected or keyed to the gear 16 and to the bearing member 19 whereby the rotation of the shaft 21 rotates the gear 16. At one end the shaft 21 is 40 provided with a crank or handle 22 adjoining the outer face of one of the sides 12 of the frame 10, while the opposite end of the shaft 21 is headed up, as at 23, against the outer face of the opposite side 12 of the frame 10.

45 It is to be observed that as each of the bearing members 19 of the hub above described operates against the inner face of one of the sides of the frame 10, the gear 16 is held against lateral displacement upon the shaft 21 or between the 50 sides 12 of the frame 10 and the latter are reinforced and maintained in their spaced positions.

It is also to be noted that the gear 16 is provided with an integral hub, the construction and 55

formation of which is relatively inexpensive requiring no assembling whatever.

What is claimed is:

1. The combination with a gear, of a tongue formed and spaced from said gear, said tongue having a shaft receiving opening therein.
2. The combination with a gear having an aperture in the center thereof, of a tongue formed from the body of the gear at one side of said aperture and bent to occupy a position at right angles to the body of the gear, the end of said tongue being lateral to cross the line of the center of the gear.
3. The combination with a gear having an aperture in the center thereof, of a tongue formed from the body of the gear at one side of said aperture and bent to occupy a position at right angles to the body of the gear, the end of said tongue being laterally bent to cross the line of the center of the gear and having an opening therein in alignment with the opening in the center of the gear.
4. The combination with a gear having a central aperture therein, a tongue formed from the body of the gear on each side of the aperture, said tongues being positioned at right angles to the body of the gear upon opposite sides thereof and having their ends bent laterally to cross the line of the center aperture of the gear.
5. The combination with a gear having a central aperture therein, a tongue formed from the body of the gear on each side of said aperture, said tongues being positioned at right angles to the body of the gear upon opposite sides thereof and having their ends bent laterally to cross the line of the center opening of the gear, said tongues having openings in the laterally bent part in alignment with the center aperture of the gear.
6. The combination with a disc, of diametrically disposed tongues formed from the body of the said disc and bent to occupy positions at angles to the disc and having shaft receiving openings adjoining their extremities.
7. The combination with a disc, of diametrically disposed tongues formed from the body of the said disc and bent to occupy positions at right angles to the disc, the ends of said tongues being bent laterally to the bodies thereof to cross the pivotal line of the disc.
8. The combination with a disc, of diametrically disposed tongues formed from the body of the said disc and bent to occupy positions at right angles to the disc, the ends of said tongues being bent laterally to the bodies thereof to cross the pivotal line of the disc, said disc and tongues being provided with aligned apertures.
9. A gear comprising a disc having an opening therein, and a tongue formed and spaced from said disc and provided with an opening aligned with the disc opening.
10. A gear comprising a disc having an opening therein, and tongues formed and spaced from said disc and upon opposite sides thereof, said tongues having openings aligned with the disc opening.
11. The combination with a disc, of tongues spaced from said disc, said disc and tongues having shaft openings aligned transversely of the disc and tongues.
12. The combination with a disc, of tongues integral with said disc and parallel thereto, said disc and tongues having shaft openings aligned transversely of the disc and tongues.

MYRON J. ZIMMER.
